tion, New York, N. Y., a corporation of Dela-
ware

Application April 20, 1949, Serial No. 88,630

3 Claims. (Cl. 34—44)

1

This invention relates to a low temperature dry cleaning apparatus, and more particularly to a condensing system adapted to be used and especially useful in condensing solvent vapors in such a low temperature dry cleaning process.

In the copending application of H. F. Hamlin, Serial No. 729,500, filed February 19, 1947, now Patent No. 2,573,966, a low temperature dry cleaning process is disclosed to which the method and apparatus of the present invention are particularly applicable. In accordance with the process disclosed in the Hamlin application, goods to be dry cleaned are introduced into a tumbler comprising a horizontal, cylindrical, rotatable drum having perforated walls and mounted in a casing in such manner that a non-aqueous solvent can be introduced into the casing and drum and the drum rotated to agitate the goods, thereby promoting effective contact between the goods and solvent to wash dirt and oily or greasy materials from the goods. Upon completion of the washing step, the solvent is drained from the goods, and the rotational speed of the drum is increased to an extent sufficient to remove solvent from the goods by centrifugal force. The speed of rotation of the drum is then decreased, the casing evacuated and residual solvent removed from the goods by bringing steam into contact with the goods under controlled conditions.

In practicing such a process it is desirable that the drying step be carried out at a relatively low temperature, e. g., 100° F. to 105° F., and since the tumbler contains liquid solvent, vapor and steam under approximately equilibrium conditions during the drying step, the desired low temperature can be conveniently maintained by controlling the pressure in the tumbler at a relatively low value. Various methods of controlling tumbler pressure might be used such as adjusting the steam flow to the tumbler, admitting a controlled flow of air to the tumbler or maintaining the steam flow constant and removing the vapors from the tumbler and condensing them at a controlled rate. Of these various methods of controlling the tumbler pressure the last is preferable from the point of view of economy and effectiveness of control. However, certain problems arise in controlling the vapor condensation rate because of the low temperatures that it is desired to use.

It is apparent that if sufficient refrigeration is used, the condensing rate may be varied as desired even at the low temperatures that are preferably employed for drying, but the use of re-

2

frigeration is expensive and for economical operation of the dry cleaning process it is necessary that less expensive cooling media, such as ordinary cooling water, be used. Moreover it is important that rapid fluctuations in the tumbler pressure be avoided and that the pressure be maintained uniformly at the desired low value. From this point of view it is desirable that a relatively small but readily controllable cooling potential be available to condense the vapors withdrawn from the tumbler and maintain the tumbler pressure in the desired manner.

Accordingly, it is an object of the present invention to provide an improved low temperature method of removing residual organic solvent from goods that have been dry cleaned with such a solvent. It is another object of the invention to provide an economical method of maintaining the pressure within a dry cleaning drier at a desired relatively low value. It is a further object of the invention to control automatically the drying step of a low temperature dry cleaning process. It is a still further object of the invention to provide apparatus for so condensing vapors from a dry cleaning drier as to maintain the drier pressure at a desired low value. Other objects of the invention will be in part obvious and in part pointed out hereafter.

The many objects and advantages of the present invention may best be appreciated by reference to the accompanying drawings which illustrate apparatus embodying the present apparatus invention and capable of being used to carry out the method of the invention. In the drawings:

Fig. 1 is a schematic drawing of a dry cleaning system showing a tumbler adapted to be used as a combination washer-drier, a condenser for condensing solvent vapors withdrawn from the tumbler, and certain auxiliary equipment;

Fig. 2 is an enlarged axial section through the condenser of Fig. 1 showing the internal construction of the condenser;

Fig. 3 is a top plan view of the condenser of Fig. 2; and

Fig. 4 is a transverse section through the condenser of Fig. 2 taken on the line 4—4 of Fig. 2.

Referring to the drawings and more particularly to Fig. 1, there is shown in the left-hand portion of this figure a combination washer-drier 13 which may be generally similar in construction to conventional tumblers used in the dry cleaning art. It comprises an outer stationary casing 12 and an inner rotatable drum 14 within which the goods are placed for cleaning. The

casing 12 is provided with a door 16 which is adapted to register with a door 18 of the rotatable drum 14 to permit introduction of the goods into the drum. The casing 12 and door 16 are made air-tight to permit the interior of the casing to be evacuated, and the casing 12 is made strong enough to withstand external atmospheric pressure when the interior of the casing is highly evacuated.

The drum 14 comprises a perforated cylindrical shell 20, the perforated end plates 22 and 23 and the flared inlet 24 through which steam passes to the interior of the drum. The central portion of end plate 23 is imperforate, that is to say, the perforations of end plate 23 are annularly arranged near the periphery of the plate to reduce the possibility of steam passing through the drum without coming in contact with the goods in the drum. Mounted on the inner surface of the shell 20 there are spaced longitudinal ribs 26 which extend radially inward toward the center of the drum and serve to lift and tumble the goods as the drum is rotated.

To rotate the drum 14 a motor 28 is provided which is connected through pulley 30, belt 32 and pulley 34 with a shaft 36 by which the drum 14 is rotated. The shaft 36 is mounted in a suitable bearing 38 and is provided with a conventional seal 40 which permits rotation of shaft 36 and at the same time prevents any substantial amount of leakage of air into the casing 12 when the casing is evacuated. The other end of drum 14 is mounted by means of the narrow portion of the flared inlet 24 in the bearings 42 and a vacuum-tight seal is provided by housing 44.

Steam and solvent may be introduced into the casing 12 and drum 14 through a pipe 46 that extends through the housing 44 and the initial portion of the flared inlet 24 to substantially the point at which the wall of the flared inlet begins to diverge. Solvent is supplied to pipe 46 through a branch pipe 48 provided with a valve 50 and steam is supplied to pipe 46 through a branch pipe 52 provided with a shutoff valve 54 and steam flow control valve 56. To remove solvent from the apparatus there is connected to the bottom of casing 12 a drain pipe 58 provided with a shutoff valve 60 and pump 62, by means of which solvent may be pumped from the casing to a solvent storage tank (not shown).

Steam and solvent vapor flow out of casing 12 through a pipe 64 which is preferably connected to the casing at several spaced points as indicated in Fig. 1. Vapors are conducted through pipe 64 to a condenser 66, which as shown in Figs. 2, 3 and 4, is of the direct contact type and will be described hereafter in connection with those figures. Continuing now to refer to Fig. 1, cooling water is admitted to the condenser 66 through a pipe 68 and condensed solvent and water flow from the condenser through a pipe 70 to a pump 72 driven by a motor 74. A check valve 71 is provided in the pipe 70 to prevent back-flow through this pipe to the condenser. The condensate is pumped by the pump 72 through pipe 76 to a separator 78 wherein the liquid solvent and water separate from each other, the solvent forming an upper layer and the water a lower layer. Solvent is removed from the separator 78 through a pipe 80 containing a shutoff valve 82. A portion of the water from the separator 78 is returned through pipe 68 to the condenser 66 and the remainder of the water flows through an overflow pipe 84 to a sewer or other point of disposal. Fresh cooling water is supplied to the

pipe 68 and thus to the condenser 66 through a pipe 86 provided with a regulating valve 88.

Connected to the top of condenser 66 by a pipe 92, containing shutoff valve 94, is a vacuum pump 90 to evacuate the tumbler 10 during the drying step. To permit venting of the system comprising the tumbler 10 and condenser 66, pipe 92 is provided with a vent pipe 96 having a shutoff valve 98. When the system is being evacuated, valve 98 is closed and valve 94 open whereas when the system is operating under atmospheric pressure, valve 98 is open and valve 94 closed.

In order to prevent excessive pressures from building up in the tumbler 10 and to maintain the tumbler pressure at the desired value certain controls are provided and operatively connected at various points in the system. Thus the steam valve 56 is of the solenoid-operated type and is energized by a pair of conductors 100 and 102 which are connected to a suitable source of energy. Connected in series in conductor 102 there is a vacuum switch 104 that communicates with the pressure within the casing 12 of tumbler 10. The switch 104 is normally closed during the drying operation but opens when the pressure within the casing rises above a predetermined value, say 5 inches of mercury absolute. During the period that switch 104 is closed, the solenoid motor of steam valve 56 is energized and the valve remains open. If for any reason the pressure within casing 12 rises above the value that causes switch 104 to open, the solenoid motor is deenergized and the steam valve 56 closes. Thus the pressure within casing 12 is automatically prevented from rising to an excessive value during the vacuum drying process.

Also connected in series with the switch 104 across the conductors 100 and 102 are a switch 106 operated by a temperature responsive element 107 located in the pipe 68 and a solenoid motor 108 for operating the water valve 88. The arrangement is such that while the switch 104 is closed the flow of water through pipe 86 is determined by operation of switch 106 which is effectively a thermostat that maintains the flow of fresh cooling water through pipe 86 at such a value as to maintain the temperature of the water supplied to the condenser substantially constant. When the switch 104 opens in response to an increase in pressure in tumbler 10, solenoid motor 108 remains deenergized and valve 88 remains closed, thus preventing further quantities of cooling water from being supplied to pipe 68 and to the condenser 66, even though the water temperature in pipe 68 may have risen above its control value.

When the pressure within the casing 12 is sufficient to open switch 104 the condensate pump 72 is automatically stopped. The motor 74 is provided with a solenoid operated switch 110 which is connected in series with the switch 104. Hence opening of the switch 104 stops motor 74 and pump 72.

As indicated above, the vapors from the tumbler 10 are condensed by being brought into direct contact with cooling water in the condenser 66, the internal structure of which is best shown in Figs. 2, 3 and 4 of the drawings. Referring to Fig. 2, the condenser 66 comprises a cylindrical casing 112 having at its lower end an integral closure plate 114 and being provided at its upper end with a peripheral flange 116 to which the cover 118 is bolted by the nuts 120. Suspended from the cover 118 and extending down

through the casing 112 of the condenser 66 there is a cylindrical condensing chamber 122. The vapor pipe 64 is connected to the top of condensing chamber 122 in such manner that vapors flowing through the pipe 64 flow downwardly through the condensing chamber 122.

Mounted within the condensing chamber 122 there is a series of water sprays 124 that spray water into the interior of condensing chamber 122 and thereby condense vapors flowing into the condensing chamber. The water supply pipe 68 is connected to a pipe 126 that is mounted in the cover 118 of the condenser 66 and extends down within the space 127 between the condensing chamber 122 and the wall 112 of the condenser. At its lower end pipe 126 is connected to a channel 128 which is formed adjacent the outer surface of condensing chamber 122 and communicates with the sprays 124 in such manner that water entering the condenser 66 flows through pipe 126 and channel 128 to and through the sprays 124.

Within the lower portion of the pipe 126 there is a valve member 130 adapted to cooperate with a seat 132 formed in the interior of the pipe to regulate the flow of water therethrough. The valve member 130 has a stem 134 that extends down through a guide 136 at the lower end of pipe 126 and engages one end of a lever 138 pivoted at 140 on the fixed support 141. The other end of lever 138 is pivotally connected to a float 142 that floats in a body of liquid at the bottom of the condenser 66. The arrangement is such that the float 142 actuates valve stem 134 to open or close the valve 130 as more fully described hereafter.

The vacuum pipe 92 is connected to the top of condenser 66 in such manner that non-condensable gases from the tumbler 10 are drawn through the condensing chamber 122, space 127 and through pipe 92 to the vacuum pump 90. At a point spaced somewhat from its lower end, the condenser 66 is provided with a liquid discharge connection 156 which is connected to the pipe 70 (see Fig. 1) through which cooling water and condensate are drawn by the pump 72. The discharge connection 156 as shown in Fig. 2 is located somewhat above the lower rim of condensing chamber 122 so that normally a body of condensate collects in the bottom of the condenser 66. At the bottom of the condenser 66 there is a drain connection 158 through which residual liquid may be drained from the condenser.

Under certain circumstances as described below there is a tendency for an excessive pressure difference to build up between the interior of the condensing chamber 122 and the space 127 within the condenser 66. To prevent such excessive pressure differences from building up, there is provided in the wall of condensing chamber 122 a liquid seal 146 comprising an open-top seal chamber 150 mounted on the exterior of the condensing chamber 122 and adapted to contain a quantity of water, and a baffle 152 extending down into the sealing liquid in the chamber. The seal chamber 150 communicates with the interior of condensing chamber 122 through an opening 148 and the construction is such that the chamber 150 is continuously supplied with water from one of the sprays 124 to maintain the water level in the seal chamber even with the bottom of the opening 148. The baffle 152 extends down into the body of water in the seal chamber 150 to an extent sufficient to pre-

vent flow of gas or vapor from the interior of condensing chamber 122 to the space 127 under normal circumstances but permits such a flow of gas or vapor when the pressure difference on opposite sides of the wall of the condensing chamber 122 exceeds a predetermined amount.

The operation of the apparatus shown in the drawings is largely apparent from its description. Goods to be dry cleaned are introduced 10 into the perforated drum 14 of the tumbler 10 and solvent is introduced into the casing 12 and drum 14 through pipe 48. The drum 14 is rotated to produce intimate contact between the goods and the solvent. The direction of rotation of 15 the drum 14 is preferably reversed periodically in the usual manner to secure effective washing of the goods.

When the washing step has been completed solvent 20 is pumped from the casing 12 by pump 62 and the speed of rotation of the drum 14 increased to cause additional solvent to be removed from the goods by centrifugal action. When such further solvent as can be removed by centrifugal action has been expressed from the goods, the 25 speed of rotation of the drum 14 is reduced, preferably to a speed such that the goods are reasonably uniformly distributed throughout the drum. Solvent inlet valve 50, solvent discharge valve 60 and vent valve 98 are then closed, vacuum valve 94 is opened and vacuum pump 90 is started to evacuate the system.

During this initial period of evacuation, a large 30 volume of air passes through the condenser 66 and, if the condensate level is above the lower edge of condensing chamber 122, the air flowing downwardly through the condensing chamber will tend to force water out of the condensing chamber and up in the space 127. The resulting drop in the water level causes float 142 to open valve 130, and water in separator 78, which is under atmospheric pressure, is drawn through pipes 68 and 126 and sprays 124 into the condensing chamber 122. Because of the large flow of air through the condensing chamber and since 35 the condensate pump 72 is not yet in operation, this water tends to accumulate in the space 127. Such an accumulation of water in space 127 is undesirable for a number of reasons. It produces a pressure drop between the interior of the tumbler and the vacuum pump, thereby preventing the pump from evacuating the tumbler to the desired extent. Moreover if the accumulation of water in space 127 is unchecked, water will 40 eventually be carried over into the suction cylinder of the vacuum pump. The seal 146 prevents such an accumulation of water in space 127. When a relatively small pressure difference has 45 been built between chamber 122 and space 127 due to flow of water into the condenser, the liquid is blown out of the seal chamber 150 and air flows from the interior of condensing chamber 122 through the opening 148 to the space 127 and thence out through pipe 92 to the vacuum pump 90. The resulting pressure equalization causes a 50 corresponding equalization of the liquid levels in space 127 and chamber 122 and float 142 is raised to close valve 130. Thus the seal 146 prevents excessive pressure differences from developing between the condensing chamber 122 and the space 127 and reduces the possibility of water being carried by the air stream into the suction cylinders of the vacuum pump 90.

When the pressure in tumbler casing 12 has been reduced to the control point of switch 104, 55 the switch closes, steam valve 56 opens, pump 72

starts removing condensate from condenser 66 and thermostat 106 is energized so that it will control the water temperature in pipe 68 by adjustment of valve 88. As pump 72 removes condensate from the condenser, the liquid level in condensing chamber 122 drops and float 142 moves downwardly to open valve 130 and permit cooling water to be drawn into the condenser.

The steam flowing into the drum 14 through pipe 46 vaporizes the residual solvent from the goods in the drum and the steam-solvent-vapor mixture passes to the condenser 66 where it is condensed by water sprayed from the sprays 124. Solvent and steam condensate and cooling water are pumped from the condenser 66 by the pump 72 to the separator 78 from which water is recirculated to the condenser through pipe 68. It has been found that the recirculated water in passing through pipe 70, pump 72, pipe 76, separator 78 and pipe 68 loses enough heat by radiation and convection so that when it is re-introduced into the condenser 66 it is capable of condensing substantial quantities of vapors therein.

If the pump 72 goes out of service or is incapable of handling the liquid discharge from the condenser 66, the liquid level in the condenser rises causing float 142 to rise to close valve 130 and cut off the cooling water supply. Thus the float 142 is effectively a safety device for limiting the water content of the condenser 66 and preventing the water level from building up in such manner as to cause condensate or cooling water to pass through pipe 92 to the vacuum pump 90.

From the foregoing description it is apparent that the present invention provides an improved method and apparatus for controlling the removal of residual organic solvent from goods that have been dry cleaned with such a solvent. The steam-solvent mixture is condensed by direct contact with cooling water and hence cooling water at the ordinarily available temperatures can be used to so control the pressure within the tumbler as to maintain a desired low temperature therein. Recirculation of the condensate and cooling medium provides operational stability and prevents sudden changes in the pressure within the tumbler. By recirculating the cooling medium and bringing it into direct contact with vapors to be condensed it becomes practicable to operate the condensing system with a very small temperature difference between the cooling medium and the vapors, thus providing a relatively small cooling potential and avoiding large or rapid changes in the tumbler pressure. Moreover substantial economies in cooling water may be effected by operating in this manner.

A controlled flow of fresh cooling medium is added through pipe 86 and mixes with the recirculated cooling medium flowing in pipe 68. Thus the heat content of the cooling medium supplied to the condenser is controlled to maintain the tumbler pressure at the desired relatively low value.

It should be understood that certain of the novel structural features described above are useful independently of the other novel structures described. For example, the vacuum switch 104 of tumbler 10 is useful in controlling the conditions under which steam is admitted to the tumbler whether the vapors leaving the tumbler are condensed in a spray condenser such as that specifically disclosed or whether they are condensed in a conventional surface condenser. Also steam jets may be used in place of the vacuum pump 90 to evacuate the tumbler 10 and

other portions of the system. Since many embodiments might be made of the present invention and since many changes might be made in the embodiment disclosed herein, it is to be understood that the foregoing description is to be interpreted as illustrative only and not in a limiting sense.

I claim:

1. In a system for removing residual quantities of a dry cleaning solvent from goods that have been dry cleaned with said solvent wherein said goods are confined in a drying chamber and exposed to the action of live steam at a reduced pressure to vaporize the solvent, the resulting solvent vapors and steam are condensed in a condenser and the resulting condensate is removed from the condenser by a pump, apparatus for controlling the operation of said system comprising, in combination, first control means for controlling the operation of said pump and second control means responsive to the pressure in said chamber and operative when said pressure drops below a predetermined value to cause said pump to be started to remove condensate from said condenser.
2. In a system for removing residual quantities of a dry cleaning solvent from goods that have been dry cleaned with said solvent wherein said goods are confined in a drying chamber and exposed to the action of live steam at a reduced pressure to vaporize the solvent, the resulting solvent vapors and steam are condensed in a condenser by being brought into direct contact with a cooling medium and the resulting condensate is removed from the condenser by a pump, apparatus for controlling the operation of said system comprising, in combination, first control means for regulating the flow of said cooling medium to said condenser, second control means responsive to the temperature of said cooling medium and adapted when energized to adjust said first control means to maintain the temperature of the cooling medium entering said condenser substantially constant and third control means responsive to the pressure within said chamber and operative when said pressure drops below a predetermined value to energize said second control means.
3. In a system for removing residual quantities of a dry cleaning solvent from goods that have been dry cleaned with said solvent wherein said goods are confined in a drying chamber and exposed to the action of live steam at a reduced pressure to vaporize the solvent, the resulting solvent vapors and steam are condensed in a condenser by being brought into direct contact with a cooling medium and the resulting condensate is removed from the condenser by a pump, apparatus for controlling the operation of said system comprising, in combination, first control means for controlling the flow of steam into said chamber, second control means for controlling the operation of said pump, third control means for controlling the flow of said cooling medium to said condenser, fourth control means responsive to the temperature of said cooling medium and adapted when energized to operate said third control means to maintain the temperature of the cooling medium entering said condenser substantially constant, fifth control means responsive to the pressure within said chamber and adapted when said pressure drops below a predetermined value to energize said first control means to cause steam to flow into said chamber, said second means to cause said pump to draw condensate

from said condenser and said fourth control means to cause said third control means to regulate the flow of said cooling medium to said condenser.
